(57) **CLAIM**

The ornamental design for a belt whip handle, as shown and described.

DESCRIPTION

FIG. 1 is a perspective view of a belt whip handle, showing my new design in use;

FIG. 2 is a front elevational view of the belt whip handle;

FIG. 3 is a rear elevational view thereof;

FIG. 4 is a top plan view thereof;

FIG. 5 is a bottom plan view thereof;

FIG. 6 is a left-side elevational view thereof, the right-side elevational view being a mirror image thereof; and,
FIG. 7 is a cross-sectional view thereof, taken along line 7--7 of FIG. 4.

The broken lines showing a portion of a whip in FIG. 1 depict environmental matter and form no part of the claimed design.
